United States Patent Office

Des. 176,880
Patented Feb. 7, 1956

176,880

STOOL FRAME

Richard M. Phillips, East Peoria, Ill.

Application September 2, 1954, Serial No. 32,150

Term of patent 14 years

(Cl. D15—8)

FIG. 1

FIG. 2

Fig. 1 is a side perspective view of a stool frame embodying my new design; and

Fig. 2 is a front perspective view of the same.

I claim:

The ornamental design for a stool frame, as shown.
